UNITED STATES PATENT OFFICE.

JAMES M. SWONGER, OF MANSFIELD, OHIO.

DIGGING APPARATUS.

1,237,578.

Specification of Letters Patent. Patented Aug. 21, 1917.

Application filed March 31, 1917. Serial No. 158,920.

To all whom it may concern:

Be it known that I, JAMES M. SWONGER, a citizen of the United States, residing at Mansfield, in the county of Richland and 5 State of Ohio, have invented certain new and useful Improvements in Digging Apparatus, of which the following is a specification, reference being had to the accompanying drawings.

10 This invention relates to certain improvements in digging apparatus and it is an object of the invention to provide an apparatus of this general character including a digging member adapted to penetrate the 15 material to be worked and which also serves as a bucket to hoist the material loosened thereby.

It is also an object of the invention to provide a novel and improved apparatus of 20 this general character including a ground working element of tubular construction and wherein its entering edge portion is provided with a flap together with hoisting means coacting with said element and engaged with 25 the flap to maintain the flap in closed position during the hoisting operation so that the digging member may serve to remove material loosened thereby.

Furthermore it is an object of the invention 30 to provide a novel and improved apparatus of this general character including a ground engaging member slidably engaged with a guideway and wherein said ground engaging member is adapted to penetrate 35 the work or material by gravitational force.

The invention consists in the details of construction and in the combination and arrangement of the several parts of my improved apparatus whereby certain important 40 advantages are attained and the device is rendered simpler, less expensive and otherwise more convenient and advantageous for use, all as will be hereinafter more fully set forth.

45 The novel features of the invention will hereinafter be definitely claimed.

In order that my invention may be the better understood, I will now proceed to describe the same with reference to the accompanying drawings, wherein—

Figure 1 is a fragmentary view in elevation illustrating a digging apparatus constructed in accordance with an embodiment of my invention;

55 Fig. 2 is a view in side elevation of the

device as shown in Fig. 1 with the flap in open position;

Fig. 3 is a view partly in elevation and partly in section taken longitudinally of the device as herein set forth; and

60

Fig. 4 is a view partly in section and partly in elevation of the device as herein embodied, the section being taken on a line at right angles to the section in Fig. 3.

As disclosed in the accompanying drawings, 1—1 denote elongated guideways preferably tubular and which are adapted to be disposed within a shaft or other opening and which are connected at their upper or outer ends by the transverse members 2 substantially permanently secured thereto and also connected by the cross member 3 slidably engaged with the guides 1 and which cross member serves as a buffer.

70 Interposed between the cross member 3 and the adjacent cross member 2 are the expansible members 4 herein disclosed as conventional coil springs encircling the guides 1. Coacting with one of the guides 1 is a pump P of any ordinary or preferred type and which affords a means whereby water may be readily withdrawn from an operation when the requirements so necessitate.

80 D denotes my improved digging member which is substantially rectangular in cross section and provided at its sides with the outstanding eyes 5 freely engaged with the guides 1 whereby it will be at once noted that the digging member D is mounted for 90 movement in a fixed line of travel. The lower portion of a face of the digging member D comprises a hinged flap 6 while the lower end of the opposite wall or face of the member D is provided with the entering edge or blade 7. In practice the flap 6 is normally in an open position and which open position is normally maintained by the spring arm 8 pivotally engaged with the flap 6 and a side of the member D.

95 In operation the member D is elevated to substantially the top of the guides 1 and then allowed to drop and the gravitational force of the member D results in the same penetrating the material or work.

100

The digging member D is adapted to be elevated in any conventional manner and includes a flexible cable 9 leading from a suitable hoisting means and extending within the member through the open top thereof

110

and provided with the flexible branches 10 anchored to the inner face of the flap 6. The cable 9 is also disposed through the tubular member 11 secured within the digging member D so that said cable is protected against contact by the material received within the member D. The tubular member 11 terminates below the upper end of the flap 6 so that the requisite closing movement is imparted to the flap 6 through the medium of the cable 9.

After the member D has been permitted to drop and penetrate the material or work the requisite strain is imposed upon the cable 9 to elevate or hoist the member D. It will be at once self-evident that the strain imposed upon the cable 9 will cause the flap 6 to assume a closed position whereby the digging member D will serve as a bucket 20 to remove the material loosened thereby. After the member D has been elevated as required the flap 6 will be opened to discharge the contents of the member D.

It is also preferred that the cable 12 be secured to the upper end of the digging member D. The cables 9 and 12 are directed around the pulleys 14 loosely mounted upon the outer or upper cross member 2. The cables 9 and 12 are adapted to be operatively engaged with a suitable hoisting apparatus and in practice after the member D has been properly elevated the cable 12 is operated to permit a slight drop of the member D so that the cable 9 will cause the flap 6 to assume an open position so that the material within the member D may be readily and conveniently dumped.

I also find it of advantage to provide the hinged end of the flap 6 and the adjacent wall of the digging member D with the outstanding lugs 15 which serve to limit the outward movement of the flap 6.

From the foregoing description, it is throught to be obvious that a digging apparatus constructed in accordance with my invention is of an extremely simple and comparatively inexpensive nature and is particularly well adapted for use by reason of

the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. An apparatus of the character described comprising a guideway, a hollow digging member slidably engaged therewith, a lower portion of the member comprising a hinged flap, a flexible lifting means coacting with the member, said lifting means being operatively engaged with the flap whereby said flap is closed upon lifting of the digger, a tubular member secured within the digging member and through which the flexible lifting means is directed, and a second lifting means secured to the digging member independently of the flap.

2. An apparatus of the character described comprising a guideway, a hollow digging member slidably engaged therewith, the lower portion of the member comprising a hinged flap, a flexible lifting means co-acting with the member, said lifting means being operatively engaged with the flap whereby said flap is closed upon lifting of the digger, a tubular member secured within the member and to the face thereof opposite the hinged flap, said tubular member having its inner end terminating below the hinged end of the flap, said flexible lifting means being disposed through the tubular member, and a lifting means secured to the digging member independently of the flap.

In testimony whereof I hereunto affix my signature in the presence of two witnesses.

JAMES M. SWONGER.

Witnesses:

JOSEPH B. LINDLEY,
MARY E. SCIOR.
